INVENTOR

BY *Victor J. Evans*

Patented Feb. 6, 1923.

UNITED STATES PATENT OFFICE.

VICTOR CLIFFORD, OF MANNFORD, OKLAHOMA, ASSIGNOR OF ONE-FOURTH TO SIMEON C. CLOVER AND ONE-FOURTH TO MARVIN K. CLOVER, BOTH OF TULSA, OKLAHOMA.

SAFETY VENT FOR HYDROCARBON CONTAINERS.

Application filed March 6, 1920, Serial No. 363,896. Renewed August 10, 1922. Serial No. 581,016.

To all whom it may concern:

Be it known that I, Victor Clifford, a citizen of the United States, residing at Mannford, in the county of Creek and State 5 of Oklahoma, have invented new and useful Improvements in Safety Vents for Hydrocarbon Containers, of which the following is a specification.

The object of my present sole invention is 10 the provision of a safety vent for hydrocarbon containers, that is efficient and reliable in preventing fire from gaining access to the interior of a container, and is so arranged and constructed as not to interfere in any 15 measure with the putting of hydrocarbon in or the removal of hydrocarbon from the container.

To the attainment of the foregoing the invention consists in the improvement as hereinafter described and definitely claimed.

In the accompanying drawings, hereby made a part hereof:

Figure 1 is a vertical section of the best practical embodiment of my invention of 25 which I am cognizant.

Figures 2 and 3 are detail sections taken in the planes indicated by the lines 2-2 and 3-3, respectively, of Figure 1.

Similar numerals of reference designate 30 corresponding parts in all of the views of the drawings.

Among other elements my novel vent comprises a conduit body made up of a T-section 1 and end sections 2 and 3. The stem 35 of the T-section 1 is adapted, by preference, to be connected to a conduit section 4 in communication with the interior of a hydrocarbon container (not illustrated).

Interposed between the head of the T-section 1 and the end sections 2 and 3 are reticulated screens 5 adapted to prevent the 40 passage of fire on the Davy lamp principle.

Connected to the body section 2 is a nipple 6 at the lower end of which is a cross-bar 7. Guided in the said cross-bar 7 and 45 extending upwardly in the body section 2 is a stem 8 that is connected to a retractile spring 10; the said spring being connected to a regulating screw 11 that bears in a 50 yoke 10^a fixed in the section 2. The stem 8 extends through a guide, and is connected thereto by readily fusible material 9. Said stem is provided at 13 with a valve body, 55 designed to cooperate with a seat 14 formed by an annulus in the section 2. Manifestly in

the event of the fusible portion of material 9 being melted by proximity to heat or fire, the spring 10 will operate to promptly draw the stem 8 outwardly and to close the valve body 13, so as to preclude the entrance of 60 fire into the vent body or into the container.

Threaded on the body section 3 is a collar 15, flanged at 16. The said collar serves to hold in the end of the body section 3 a seat 19 for a valve body 20, carried by a 65 stem 21 which has a readily fusible portion at 22 and is connected at its upper end to a regulating screw 11, carried by a yoke 10^b in section 3. The fusible portion 22 will be melted by proximity to heat or fire, and 70 when the portion 22 is so melted, the valve body 20 will be seated by gravity, so as to preclude outward passage of gases through the body section 3.

By reason of the construction of my improvement, adequate venting of gas from a hydrocarbon container is assured at all times under normal conditions, with the result that safety is promoted. It will also be apparent that under normal conditions the reticulated screen 5 may be depended upon to prevent fire from gaining access to the interior of the container. When both fusible portions 9 and 22 are melted to release the 80 valve bodies 13 and 20 in the manner and 85 for the purpose before alluded to, it will be apparent that the vent will still be in condition for practical operation, this because incidental to the operation of pumping hydrocarbon from the container, the valve body 13 will open outwardly to permit the 90 passage of excess pressure in the container and thereby relieve the container, while the opening of the valve body 20 by suction in the container will preclude the possibility 95 of a vacuum or partial vacuum being created in the container, such as would interfere with the free passage of hydrocarbon therefrom.

The apparatus herein disclosed has proved 100 in actual practice to be reliable and otherwise successful.

Having described my invention, what I claim and desire to secure by Letters-Patent, is:

1. A vent for hydrocarbon containers comprising a conduit body having a T-section and elbow sections joined to the ends of the T-head, reticulated screens secured between the ends of the T-head and said elbow 110

- sections; a valve seat in one elbow section, a cross bar connected to the section, a regulating screw mounted in the elbow section, a stem interposed between and connecting said 5 cross-bar and said screw and including a retractile spring and having a readily fusible portion connecting it to the cross-bar, an inwardly seating valve body carried by said stem and opposed to said valve seat, a valve 10 seat in the other elbow section, an outwardly seating valve body opposed to said seat, a regulating screw bearing in said elbow section, and a stem connecting the valve body and said screw and including a readily fusible portion.
2. A vent for hydrocarbon containers comprising a conduit body of general T-form, an inwardly seating valve body opposed to one end of the conduit body, a stem 20 connected with the valve body, readily fusible means to hold said stem against move-

ment, yielding means connected to said stem and adapted in the event of dissolution of the readily fusible means to close the valve body, and an outwardly seating valve body 25 adapted to control the other end of the conduit body and normally held against seating by means including a readily fusible portion.

3. A vent for hydrocarbon containers having two orifices; one of the said orifices being controlled by an inwardly seating valve and the other orifice by an outwardly seating valve, and the inwardly seating valve being connected with spring means for closing the same and being normally held against closing by means including a readily fusible portion. 30

In testimony whereof I affix my signature.

VICTOR CLIFFORD. 40
